United States Patent Office

Des. 215,497
Patented Sept. 30, 1969

215,497

IMPACTING MACHINE

Franklin M. Frohnauer, Jr., 790 S. Cassingham Road,
Columbus, Ohio 43209

Continuation-in-part of design application Ser. No. 87,821,
Oct. 19, 1965. This application Feb. 1, 1967, Ser. No.
8,311

Term of patent 14 years

Int. Cl. D15—04

U.S. Cl. D60—1

FIG. 1

FIG. 2

FIG. 3

FIG. 4

FIGURE 1 is an over-all perspective view, of an impacting machine showing my new design.

FIGURE 2 is a left side view of the design of FIGURE 1.

FIGURE 3 is a front view of the design of FIGURE 1.

FIGURE 4 is a back view of the design of FIGURE 1. The dominant features reside in the solid line portions.

This application is a continuation-in-part of my design application Ser. No. 87,821, filed Oct. 19, 1965, for Impacting Machine, and now abandoned.

I claim:

The ornamental design for an impacting machine, as shown and described.
